UNITED STATES PATENT OFFICE

EARL LEO BILHEIMER, OF BONNE TERRE, MISSOURI, ASSIGNOR TO ST. JOSEPH LEAD COMPANY, OF NEW YORK, N. Y., A CORPORATION OF NEW YORK

PUNCHING TOOL FOR PRIMER CARTRIDGES

Application filed September 1, 1931. Serial No. 560,368.

The invention relates to a special tool for punching or forming a longitudinal fuse receiving opening in powder sticks employed in blasting operations and, to this end, comprises a tubular casing having an internal diameter to substantially fit the powder stick and a punch rod secured centrally in and extending longitudinally of the casing adapted to form a longitudinal bore or opening of definite length and position in the stick when the latter is forced into the casing.

The invention is illustrated in the accompanying drawings, in which:—

Fig. 1 illustrates a typical stick of blasting powder with a fuse and cap secured in the longitudinal opening therein.

Fig. 2 is a longitudinal section through the tool.

Fig. 3 is an end elevation of the tool.

Fig. 4 is a view similar to Fig. 2, with the casing removed.

Fig. 5 is an end elevation of the plug.

In blasting operations, involving the explosion of sticks of blasting powder, such as dynamite inserted in series in a suitable drill hole formed in the material to be blasted, it is customary to explode the charge by means of a primer cartridge, which consists of a stick of dynamite or blasting powder in which has been inserted a detonator, usually known as a dynamite cap, which is exploded by the application of heat supplied by a fuse to the end of which the cap is crimped. The fuse ordinarily employed is generally of rope-like form with a continuous central core of powder or similar material that burns, when ignited, at a substantially uniform rate. To secure the best results, the fuse, which is cut to proper length, and the cap or detonator crimped to the end of the fuse, are inserted into an opening formed in the primer cartridge or stick of blasting powder, so that, when the fuse burns down to the charge in the cap or detonator, said charge is exploded and this explosion detonates the primer cartridge, which, in turn, detonates the other cartridges or powder sticks in the drill hole. If, for any reason, the primer cartridge fails to explode after the charge has been ignited, the unexploded charge becomes a serious

hazard to the lives of those who have to deal with it. It therefore becomes very important that the primer cartridge be prepared with careful attention to details to provide, as far as practicable, against failure to function properly. Furthermore, since there is an element of danger in handling dynamite caps or detonators, especially with dynamite cartridges or sticks nearby, it is also important that the equipment used to prepare the primer cartridge be designed and arranged to reduce the hazard to the workmen as far as possible.

The present invention is designed primarily to reduce the danger in preparing and assembling the primer cartridges, more especially in preparing the bore or hole in the powder stick, which receives the associated detonator and length of fuse, by providing means for forming the bore or longitudinal opening in the powder stick so that the fuse and detonator may be properly and accurately positioned within the stick. The special tool of my invention involves a tubular casing 1, preferably made of brass or similar metal, which is designed to receive a stick of blasting powder, which is usually cylindrical, the bore of the tubular casing being of sufficient diameter to accurately guide the powder stick into telescoping engagement with the casing. One end of the casing, in the exemplification here shown, is provided with a plug 2, which may be united to the interior of the casing by brazing or the like, in the center of which plug is mounted a pointed punch rod 6, which is thus maintained in alignment with the longitudinal axis of the casing and of the powder stick to be perforated. Preferably, the plug 2 has secured to its outer face a handle 7, which may conveniently take the form of a section of rod brazed to the plug by means of which the tool is manipulated. The plug 2 is preferably provided with a series of openings 3 and the casing 2 adjacent the plug with openings 5, which permits the escape of granular material or dirt which might accumulate in the tool and also allow the venting of the casing when the latter is forced in telescoping engagement with the powder stick.

In applying the tool to its intended use, the stick of powder or dynamite is telescopically engaged with the open end of the casing until the sharp end of the pointed rod 6 engages the entering end of the stick. By exercising a pressure on the handle 7 by one hand and the dynamite stick by the other, the punch rod 6 is forced accurately through the center of the stick, forming a clean cut bore or opening of the desired depth. If direct pressure fails to produce the desired puncture, a relative rotary motion between the tool and the powder stick will materially aid in the formation of a clean hold in the stick.

10 After the hole has been punched to the desired depth, the powder stick is withdrawn from the casing and the detonator cap with the proper length of fuse applied thereto is applied in the manner and form illustrated in

15 Fig. 1, so that the assembly constitutes an effective primer cartridge for firing a main charge.

While the element for supporting the punch rod is shown as a plug, it will be understood that the same may take any other appropriate form provided it constitutes a rigid support which will maintain the punch rod in accurate alignment with the longitudinal axis of the tubular casing.

20 What I claim is:

1. A tool for punching longitudinal fuse receiving openings in powder sticks, comprising a tubular casing having a longitudinal diameter to fit the powder stick, a plug secured at one end of the casing, and a punch rod secured centrally in said plug and extending longitudinally of the casing.
2. A tool for punching longitudinal fuse receiving openings in powder sticks, comprising a tubular casing having a longitudinal diameter to fit the powder stick, a plug secured at one end of the casing, a punch rod secured centrally in said plug and extending longitudinally of the casing, and a handle secured to said plug.
3. A tool for punching longitudinal fuse receiving openings in powder sticks, comprising a tubular casing having a longitudinal diameter to fit the powder stick, a plug secured at one end of the casing, and a punch rod secured centrally in said plug and extending longitudinally of the casing, the plug being provided with vent and cleaning openings.
4. A tool for punching longitudinal fuse receiving openings in powder sticks, comprising a tubular casing having a longitudinal diameter to fit the powder stick, a plug secured at one end of the casing, and a punch rod secured centrally in said plug and extending longitudinally of the casing, the plug and the casing being provided with vent and cleaning openings.
5. A tool for punching longitudinal fuse receiving openings in powder sticks, comprising

ing a tubular casing having a longitudinal diameter to fit the powder stick, a plug secured at one end of the casing, a punch rod secured centrally in said plug and extending longitudinally of the casing, and a handle secured to said plug, the plug and the casing being provided with vent and cleaning openings.

In testimony whereof I affix my signature.

EARL LEO BILHEIMER.
